NICHOLAS E. OGLESBY AND DAY EHRENFIELD, OF EDGEWOOD, MARYLAND, ASSIGNEES,
BY MESNE ASSIGNMENTS, TO FEDERAL LABORATORIES, INC., OF PITTSBURGH, PENN-
SYLVANIA, A CORPORATION OF DELAWARE

PROCESS OF MAKING A COMPOSITION FOR PRODUCING IRRITATING GAS

No Drawing. Application filed April 30, 1924, Serial No. 710,171. Renewed December 26, 1930.

(GRANTED UNDER THE ACT OF MARCH 3, 1883, AS AMENDED APRIL 30, 1928; 370 O. G. 757)

This invention described herein may be manufactured and used by or for the Government for governmental purposes without the payment to us of any royalty thereon in accordance with the act of March 3, 1883, as amended by the act of April 30, 1928.

This invention relates to a process of making a composition for producing an irritating gas used in devices such as shells, grenades, 10 candles, etc.

Among the objects of this invention is the production of a composition which may be employed in devices such as shells, grenades, candles, etc. for producing an irritating gas, which composition will remain stable and undergo practically no decomposition and generate the irritating gas in a highly efficient method whereby substantially no decomposition of the gas will occur upon its 20 generation.

A still further object of this invention consists in a method of loading devices such as shells, grenades and candles, with a composition which will produce an irritating gas 25 when the device functions, and which device will not explode when fired.

In carrying out our invention, we employ an irritant, for example capsaicin or diphenylchlorarsine, or more preferably an irritant which is also lachrymating, for example chloracetophenone, bromacetophenone or iodoacetophenone and add to this irritant an explosive fuel, for example a mixture of ammonium nitrate and charcoal, black powder, nitrocellulose (smokeless powder) or ballistite (a solid solution of nitrocellulose in nitroglycerine). There is usually added to this mixture for the purpose of stabilization an anti-acid, such as MgO and ZnO, which 40 tends to overcome or counteract the tendency for slow decomposition to develop in the mixture after preparation.

In adapting compositions of the character heretofore described to grenades or similar devices, the following requirements should be satisfied if an efficient device and satisfactory operation are to be obtained:

1. Flashing or ignition at the orifice with consequent burning when the volatilized mixture comes in contact with the air should

be avoided since this will decompose the irritant and destroy its effectiveness for the purpose desired.

2. Bursting of the container should be avoided.

3. There should be simple and positive ignition of the mixture.

In filling the grenade, candle, or shell, loose mixtures do not give the best results. For example, in grenades the loose mixtures 60 will at times cover or plug the orifices with which these grenades are provided and thus cause the grenade to explode upon generation of gases therein. In order to avoid these explosions, the mixtures should be well caked. 65

In loading a grenade or similar device with mixture of capsaicin or chloracetophenone with fuels, such as ammonium nitrate and charcoal, pressure alone may be used for the caking operation and the exposed end of the cake is preferably painted with some good binding material, such as a solution of shellac, in order to prevent breaking up of the cake under conditions of handling and use. 70

Owing to the greater tendency for decomposition of the irritant when employing a fuel such as black powder, or ammonium nitrate and charcoal, we prefer to use the irritant with a fuel such as nitrocellulose or 80 ballistite. When employing mixtures of chloracetophenone and smokeless powder, if pressure alone is employed in the caking process, the product will not be as uniform or operate as efficiently or functioning as desired, and likewise there is present the danger of the parts of the mixture breaking loose and covering the holes provided for the escape of gases from these devices, thus causing the grenade or similar device to explode 85 when fired. Some of the methods of overcoming these difficulties under various conditions are as follows:

A. The chloracetophenone, small calibre smokeless powder (.30 cal. rifle powder is 95 quite satisfactory) and MgO are intimately mixed and the required amount of the mixture is tamped into the container, and a solvent for the smokeless powder, such as acetone, is poured uniformly over the top of 100

the mixture in sufficient amount to thoroughly moisten the mixture for a depth of $\frac{1}{2}$ to 1 inch and the mixture is again tamped. When dry, the top of the mixture is hard, 5 compact and firm.

B. A mixture of chloracetophenone, smokeless powder and MgO is intimately mixed as under (A), and the required amount placed in the container. The container is then heated 10 and the mixture pressed or tamped until compact. The heating should be sufficient to melt the chloracetophenone in order that the mixture will tamp or press compactly, but overheating should be avoided as this will result in a solution of smokeless powder in chloracetophenone, which will not remain fluid at or below 100° C. and the mixture will not press or pack well. This method of loading is preferable to that described under (A), 15 since the cake produced under (A) has a tendency to break up on "set back" when fired from a rifle because only the top surface of the cake is firmly bound. Likewise evolution of gas from grenades loaded by method (A) is not uniform which is probably due to the difficulty of uniformly evaporating the acetone that is added during the process.

The method of loading under (B) is rapid and very satisfactory and particularly adapted for devices of small cross-section, but since the mixture is a poor heat conductor, this method of loading will not operate where containers of large sectional area are employed, for example certain smoke candles 20 and large shells.

C. In this method of loading, the MgO is stirred into molten chloracetophenone and the small calibre smokeless powder, preferably heated, is added and thoroughly mixed 25 with the molten chloracetophenone and suspended MgO. While the mixture is hot and plastic it is pressed into the container. This method has been found very satisfactory for chloracetophenone smoke candles having a diameter of about 4 inches. When this mixture is pressed into the candle, on cooling substantial contraction takes place and the cooled mass will not fill the container, thus resulting in a substantial increase of surface exposed to burning. This space should be filled 30 either with molten chloracetophenone, paraffin, or other material which is either inert or adds to the efficacy of the mixture. When deep containers are employed, the opening 35 between the caked mass and the walls of the vessel cannot ordinarily be filled as satisfactorily as desired with the chloracetophenone or paraffin by simply pouring the material into the opening. We therefore prefer the following method for loading devices having 40 deep containers, for example a Stokes shell.

D. In loading a Stokes shell, the smokeless powder of large calibre (12-inch rifle powder is satisfactory) is stacked in layers in the shell, warmed and then molten chloraceto-

phenone carrying the MgO in suspension is poured into the shell and allowed to flow down through and into the smokeless powder. This smokeless powder is ordinarily in the form of cylindrical blocks or cakes having holes extending longitudinally, and these holes become filled with the molten chloracetophenone and suspended MgO. If it is desired to increase the ratio of smokeless powder to chloracetophenone in the mixture 70 and thereby increase the speed of burning or evolution of the chloracetophenone, small calibre powder may be introduced between the large blocks or cakes before adding the molten chloracetophenone. 80

E. In some devices, due to the irregular shape of the container, regular stacking of the blocks of smokeless powder cannot readily be done. A satisfactory method for loading such containers consists in stirring MgO 85 into molten chloracetophenone and then adding warm smokeless powder thereto, the mixture being kept stirred until cold. By this procedure a granular form of material is obtained, wherein each grain of powder 90 is coated with chloracetophenone. The granular material is then tamped or pressed into the container and the top of the mixture covered with a layer of a hot, plastic mixture of chloracetophenone, smokeless powder and MgO. When cold, this layer holds the filling in place. 95

F. Another very satisfactory method of loading consists in mixing thoroughly warm smokeless powder, MgO and molten chloracetophenone and then pressing the mass into cakes or blocks by means of dies of suitable size and shape. These cakes or blocks are then dipped in a bath of molten chloracetophenone and then slipped into the container which is made to closely fit the cake or block. The purpose of dipping the block in the molten chloracetophenone is to provide an outer surface of chloracetophenone on the block which serves to prevent burning down the sides of the block. A device loaded in this manner will give a uniform evolution 105 of irritating or lachrymating gas without explosion of the device. 110

For positive ignition of the mixture of irritant, fuel and stabilizer, considerable heat is necessary and a composition known as a starter is employed therefor. This starter may be held in a separate tube or container 115 and allowed to melt through and ignite the mixture. However, if the starter is carried in a tube which melts and produces a slag, this slag will tend to ignite the chloracetophenone vapors, causing what is known as flashing. Also, if the starter is held in a weak 120 container, such as paper, it has a tendency to blow through the container and the ignition is not satisfactory. 125

We have overcome the disadvantages incident to the use of a starter in a separate tube 130

- by binding the starter directly to the mixture. A suitable starter composition for this purpose consists of meal powder (fuse powder or very finely-divided black powder) which is bound with celluloid dissolved in acetone. This starter operates very satisfactorily with mixtures having a high ratio of powder to chloracetophenone (as is the case with grenades), but when operating with mixtures of lower ratios of powder to chloracetophenone, as for instance the candles, iron oxide and FeS are added to the meal powder and the mixed starter is bound to the chloracetophenone-smokeless powder-MgO mixture with celluloid dissolved in acetone. The use of a solvent for nitrocellulose or smokeless powder binds the starter to the powder in the chloracetophenone-smokeless powder-MgO mixture.
- 20 To ignite the starter used in our devices, the spit from ordinary safety fuses, the flash from a match head or any similar spit or flash may be employed in connection with any suitable firing mechanism.
- 25 A suitable starter composition for use with mixtures having a high ratio of powder to chloracetophenone, especially where small calibre powder is used, may be made from substantially equal parts of meal powder and a 3½% solution of celluloid dissolved in acetone. For mixtures of low ratio of powder to chloracetophenone a suitable starter paste may be made by thoroughly mixing 2 parts of a dry starter to 1 part of a binding solution, the dry starter consisting of:
Fe (100 mesh)	1 part
Hammer scale or iron oxide (80 mesh)	1 part
40 Meal powder	2 parts
- The binding solution may consist of a solution of celluloid in acetone of about 4%.
- In using mixtures of nitrocellulose and chloracetophenone, the proportions may vary from 1 to 5 parts of nitrocellulose for 1 part of chloracetophenone. If MgO is employed as a stabilizer it should preferably vary from about 8 to 12% of the weight of chloracetophenone used in the mixture.
- 50 In addition to the methods heretofore described, the cake of fuel may be prepared without the aid of heat, and if it is desired to mix the materials in the cold and without previously melting or liquefying one or more of the components, the irritant and the fuel in dry form, with or without a stabilizer, may be treated with a solution of an adhesive or binder, for example glue, or preferably a binder of low melting point for example paraffin, pitches or bituminous materials, and the mass placed in the container, tamped and allowed to dry. The methods heretofore described which employ heat or molten materials are, however, preferable in most instances 65 to this cold process.

In the following claims, the term "gas" is used to include substances which are in the gaseous phase as well as substances which are commonly termed smokes, clouds, vapors, mists, etc. and combinations of these.

The present invention is not limited to the specific details set forth in the foregoing examples which should be construed as illustrative and not by way of limitation, and in view of the numerous modifications which may be effected therein without departing from the spirit and scope of this invention, it is desired that only such limitations be imposed as are indicated in the appended claims.

We claim as our invention:

1. In a process of making a composition for producing an irritating gas, molding a heated mass of a liquefied irritant which is solid at ordinary temperatures, an intimately distributed fuel which burns at a temperature sufficient to volatilize the irritant but below that at which the irritant will decompose within the time required for said volatilization and an anti-acid for preventing or retarding decomposition of the mixture of the irritant and fuel and then coating the molded mixture with said irritant in a liquefied condition.

2. In a process of making a composition for producing an irritating gas, molding a heated mass of liquefied chloracetophenone having intimately distributed therethru nitrocellulose and magnesium oxide and then dipping and molded mixture in liquefied chloracetophenone.

3. A process for making a composition for producing an irritating gas comprising intimately mixing a fuel, an irritant, solid at ordinary temperatures, a composition to retard the combustion of the irritant and fuel mixture, coating the mixture with a volatile solvent, and evaporating the solvent.

4. In a process of making a composition for producing an irritating gas, thoroughly mixing warm smokeless powder and magnesium oxide with molten chloracetophenone, molding the heated mixture into cakes, and dipping said molded cakes into liquefied chloracetophenone.

CERTIFICATE OF CORRECTION.

Patent No. 1,864,754.

June 28, 1932.

NICHOLAS E. OGLESBY ET AL.

It is hereby certified that error appears in the printed specification of the above numbered patent requiring correction as follows: Page 3, line 99, claim 2, for "and" read said; same page, strike out lines 101 to 107, comprising claim 3, and for claim number "4" in line 108, read 3; and that the said Letters Patent should be read with these corrections therein that the same may conform to the record of the case in the Patent Office.

Signed and sealed this 6th day of September, A. D. 1932.

(Seal)

M. J. Moore,
Acting Commissioner of Patents.
